Attorney

UNITED STATES PATENT OFFICE.

WILLIAM MORE DECKER, OF BUFFALO, NEW YORK.

NURSING DEVICE.

1,099,082.

Specification of Letters Patent. Patented June 2, 1914.

Application filed May 26, 1911. Serial No. 629,745.

To all whom it may concern:

Be it known that I, WILLIAM MORE DECKER, a citizen of the United States, residing at Buffalo, in the county of Erie and State of New York, have invented new and useful Improvements in Nursing Devices, of which the following is a specification.

My invention relates to nursing devices for infants.

10 The object of my invention is to produce a sanitary and economical nursing device in which the parts receiving the greatest wear are separable and may be renewed at slight expense.

15 A further object thereof is to provide a nursing device with a flexible breast to be separably secured on a food cell, and a flexible nursing nipple separably attached to the breast.

20 Another object of my invention is to produce a flexible breast and nursing nipple for a nursing device adapted to be readily and securely coupled together for use, and thereafter conveniently uncoupled for 25 cleansing and sterilizing and for the renewal of their parts.

A still further object thereof is to produce a flexible breast or dome for a nursing device provided with a suitable opening for 30 the insertion of a flexible nursing nipple which is provided with a flaring flange around its base, the adjacent and contacting parts of said breast and nipple being suitably shaped and reinforced to form a liquid-tight separable jointure for coupling same 35 together in use, and still another object thereof is to produce a more simple, cheap, and efficient article of said class than has heretofore been provided.

40 To these ends, my invention includes the combinations and arrangement of component parts to be hereinafter described and more particularly pointed out in the claim.

In the accompanying drawings, in which 45 like reference characters indicate similar parts, Figure 1 is an elevation of my nursing device assembled; Fig. 2 is a vertical sectional view of the same; Fig. 3 is a sectional view of the parts of my device disassembled; Fig. 4 is a sectional view of a modified form of the nipple of my invention; Fig. 5 is a perspective view of the nipple shown in Fig. 4, and Fig. 6 is a sectional view of another form of a nursing nipple.

55 My invention includes generally, a cylindrical food receptacle, preferably of the

wide mouth form, a dome or breast of flexible material such as rubber, having an opening in the top thereof for the insertion of a nursing nipple, and a nursing nipple 60 provided with a flaring annular flange surrounding its base and conforming to the shape of the inner side of the dome.

Referring now to the drawings, 1 indicates a cylindrical food cell having one end 65 open, around the mouth of which is provided the annular flange or head 2.

3 indicates a dome shaped breast, of relatively flexible and elastic material, such as rubber, which is open at its base, and is 70 provided with the inwardly extending annular flange or head 4 adjacent to its lower edge adapted to engage the flange 2 around the mouth of the food receptacle when assembled thereon. Said breast is provided 75 with a circular opening 5 at its top, the edges of which at 6 are beveled inwardly to conform to the contour of the walls of the nipple hereinafter described. The walls of said breast 3, as shown in the drawings are 80 reinforced by thickening same adjacent to the opening at the top, from which they gradually taper and diminish in thickness toward the base, for the purpose hereinafter described.

85 As shown in the drawings, the nursing nipple 7 is inserted through the opening 5 in the top of the breast. In the preferred embodiment of my invention, said nipple is substantially conical in shape, when in repose, having the nursing vent 8 at its apex, and surrounded at its base by an outwardly extending annular flange 9 which forms an angle with the body portion of the nipple, and is designed to snugly conform 95

to the inner wall of the breast adjacent to its upper opening. Said nipple is of flexible and elastic material, such as rubber, and its walls are slightly thickened at 9 below the base of the conical portion thereof to 100 afford sufficient pressure and reinforcement to hold same in assembled position in the dome. Said nipple is of slightly greater diameter about its base than the diameter of the opening 5 in the top of the breast, 105 for the purpose of exerting an outward pressure on the walls of the breast when inserted therein, and for forming a bulb-shaped structure above the breast as shown in Fig. 2 of the drawings. The flange 9 of the 110 nipple tapers to a thin edge at its outer extremity 10 to avoid forming an obstruc-

tion or shoulder against the inner wall of the breast. The breast and nipple, thus described, may be assembled in position before or after the breast has been attached to the food cell. If they are assembled prior to attachment on the food cell, the nipple may be introduced through the inside of the breast by compressing the bulb, but it may also be inserted through the top of the breast by compressing the flange at its base. When thus assembled, it will be appreciated that the reinforced and thickened structure of the upper part of the breast will support and yieldingly sustain the parts in their assembled relation, and that the expansion pressure of the nipple and flange will form a liquid tight coupling with the breast, the adjacent and contacting faces being molded to register and conform when assembled. It will further be appreciated that the structure thus formed provides a flexible and yielding device simulating the breast and nipple of a mother, and that the parts may be conveniently separated for cleansing and sterilizing, or for the renewal of the nipple portion should same become worn out without the necessity of providing an entirely new breast as well.

I do not desire to be limited to the particular form of nursing nipple shown in the preferred embodiment of my invention, and have, therefore, shown in Figs. 4 and 5 of the drawings, a modified form thereof. In said view, the nipple comprises the base 10' surrounded by the annular flange 9 of substantially the same structure as that shown in the preferred embodiment, upon which rises the substantially cylindrical flexible structure 11 which is entirely open

at the top. The base 10' is provided with 40 the central nursing orifice 12 to permit the flow of food from the cell. As shown in the drawings, the interior of the cylindrical structure of said nipple is provided with a plurality of longitudinal ribs 13 adapted to 45 prevent the collapse of the cylinder in such manner as to obstruct the flow of food. In the form of nipple last described, it will be appreciated that the location of the base 10' in substantial alinement with the top 50 walls of the breast will provide a more substantial expansive pressure to prevent the displacement from assembled relation and that the location of the nursing orifice in the base thereof avoids the contracting and expanding in nursing and thus regulates the steady flow of the food therethrough, and the orifice, thus protected, remains at a fixed size for a much longer nursing period, and regulates nursing. 55

Having thus described my invention, what I claim as new and desire to have secured by Letters Patent, is—

A nursing device, comprising a flexible breast adapted to be detachably secured 65 upon a food cell and having an opening at its top, the edges of said opening being beveled inwardly, and a flexible nipple of slightly greater diameter than the diameter of the opening secured in said opening, said 70 nipple having an outwardly extending annular flange at its base conforming to the shape of the inner side of said breast, substantially as described.

WILLIAM MORE DECKER.
